UNITED STATES PATENT OFFICE.

CHARLES H. MURRAY, OF NEWCASTLE-UPON-TYNE, ENGLAND, ASSIGNOR TO
W. G. ARMSTRONG, MITCHELL & CO., (LIMITED,) OF SAME PLACE.

HYDRAULIC OPERATING MECHANISM FOR ORDNANCE.

SPECIFICATION forming part of Letters Patent No. 377,905, dated February 14, 1888.

Application filed June 15, 1887. Serial No. 241,331. (No model.) Patented in Italy December 31, 1886, No. 20,755.

To all whom it may concern:

Be it known that I, CHARLES HENRY MURRAY, of The Elswick Works, Newcastle-upon-Tyne, England, engineer, a subject of the Queen of Great Britain, have invented certain new and useful Improved Means for Controlling Hydraulic Apparatus Used for Elevating Heavy Guns, (for which a patent has been obtained in Italy, dated December 31, 1886, No. 20,755,) of which the following is a specification.

In hydraulic apparatus for controlling the elevation given to heavy guns I fit a small D-valve to pass the water to and from the elevating-cylinder, and so arranged that the D-valve having been opened by hand-gear is shut by the action of the sighting-gear shafts, which move always in exact accord with the elevating-gear; or a separate train of gear might be provided for the valve-closing mechanism. To do this I fit to each sighting-shaft a worm-wheel, into which a short worm carried on a shaft connected with the spindle of the D-valve can gear. The said worm-shaft is turned by hand-gear, and the worm-wheel, not being able to turn the shaft with the worm upon it, moves longitudinally in its bearings and carries the D-valve with it. The valve passes water to or from the elevating-cylinder, which, in making its stroke, carries the sighting-shafts round and so turns the worm-wheel. By this movement the worm-shaft is again moved longitudinally, and the D-valve is thereby closed. The advantage of this arrangement is, that a definite movement of the hand-wheel will be followed by a certain movement of the elevating-gear and of the gun and sights, and it will not be necessary to attend to the stopping of the movement, as the gear will stop itself. This arrangement is particularly for use for fine laying of the guns at the sighting-station, and as it will be necessary to have additional valves to quickly bring the guns to loading positions, and as these other valves will effect a movement of the sighting-shaft, I provide for the sighting-shaft moving without breaking the worm or worm-wheel by attaching the worm-wheel to the sighting-shaft by a friction-coupling, which will slip when an undue strain comes upon it.

The drawings hereunto annexed show elevat-

ing-gear for heavy guns arranged as above described.

Figure 1 is a side elevation, mainly in section, of a revolving turret in which is a gun-mounting fitted with the elevating-gear; and Fig. 2 is a plan view of the same. Figs. 1^a and 2^a are parts of Figs. 1 and 2 on a larger scale.

A is the ordinary slide, along which the gun-carriage B recoils when the gun is fired. The slide is pivoted at its forward end on a horizontal joint, A', and its rear end is supported by the ram C of the hydraulic cylinder D. The required elevation is given to the gun by allowing water under pressure to pass to or escape from the cylinder.

E is a toothed rack on the under side of the gun-slide. It gears with a toothed wheel, F, and gives motion by way of a toothed wheel to a transverse shaft, G. On this shaft is a pinion, H, which gears with a toothed rack on the sight-bar, I, which indicates the elevation which has been given to the gun.

K is a slide-valve for controlling the admission of water to or its escape from the cylinder D. Water under pressure passes to the valve-chamber through the pipe L. When the valve is shifted endwise in one direction, the water is free to pass from the valve through the pipe M to the cylinder, and when the valve is shifted endwise in the opposite direction water is free to pass away from the cylinder and to escape through the pipe N. The shifting endwise of the valve in one or the other direction is effected by its being coupled at O to an upward-ly-projecting shaft, P, which is not only free to turn in either direction in its bearings, but also to move endwise through them. The shaft has a worm, R, upon it. This gears with a worm-wheel, S, fixed upon the shaft G. When the shaft is turned by its hand-wheel T, the shaft is moved endwise in its bearings, as the wheel S is not free to turn. As it moves endwise it carries the slide-valve K along with it, and either allows water to pass to the cylinder or to escape from it. This causes the transverse shaft G, and consequently the wheel S, to be revolved, and as it turns it draws the worm R, shaft P, and valve K back into their former position, and again closes all passage of water to or from the cylinder.

In the drawings I have shown one train of

gear-wheels as being used not only for closing the valve, but also for actuating the automatic sighting-gear; but it is not essential that this should be so. A separate train of gear might 5 be provided for the valve-closing mechanism.

Having now particularly described and ascertained the nature of my said invention and in what manner the same is to be performed, I declare that what I claim is—

10 1. The combination of the front pivoted gun-slide, the supporting ram and cylinder beneath the gun-slide for vertically adjusting it at rear, the pipes and valve controlling the passage of liquid to and from the cylinder, the transverse 15 shaft beneath the gun-slide and between its pivot and the ram, the gear connecting the gun-slide with the transverse shaft, the worm-wheel fixed on this shaft, the endwise-moving shaft adapted to be turned in either direction 20 and coupled with the controlling-valve, and the worm on this shaft engaging the worm-wheel on the transverse shaft, substantially as and for the purpose set forth.

2. The combination of the front pivoted gun-slide, the supporting ram and cylinder beneath 25 the gun-slide for vertically adjusting it at rear,

the pipes and valve controlling the passage of liquid to and from the cylinder, gearing operating the controlling-valve and connected with the gun-slide, which gearing is actuated by 30 hand to open the valve and automatically actuated to close the valve, and the sight-bar, also gear-connected with the gun-slide, substantially as and for the purpose set forth.

3. The combination of the front pivoted gun-slide, the supporting ram and cylinder beneath the gun-slide for vertically adjusting it at rear, the pipes and valve controlling the passage of liquid to and from the cylinder, the downwardly-projecting rack of the gun-slide, the 40 transverse shaft actuated by said rack and having the worm-wheel, the endwise-moving shaft coupled with the controlling-valve and having the worm engaging with said worm-wheel, and the sight-bar geared with the transverse shaft, substantially as and for the purpose set forth. 45

C. H. MURRAY.
